(57) **CLAIM**

The ornamental design for a portable video camera, as shown and described.

DESCRIPTION

FIG. 1 is a top, front and right side perspective view of a portable video camera showing our new design;
FIG. 2 is a front view of the portable video camera;
FIG. 3 is a rear view of the portable video camera;
FIG. 4 is a left side view of the portable video camera;
FIG. 5 is a right side view of the portable video camera;
FIG. 6 is top view of the portable video camera; and,
FIG. 7 is a bottom view of the portable video camera.
The broken lines depict portions of the portable video camera in which the design is embodied that form no part of the claimed design.
